UNITED STATES PATENT OFFICE

2,354,908

RADIO WITH VACUUM CHAMBER

Abraham Binneweg, Jr., Oakland, Calif.

Application August 24, 1942, Serial No. 455,857

1 Claim. (Cl. 250—27.5)

My invention relates to improvements in vacuum tubes and the object of my improvement is to provide a compact radio cabinet with several compartments and especially with a vacuum sealed compartment containing multiple units connected by short leads for ultra short wave reception or transmission. Other objects are to provide special mountings for cathodes, grids, plates, and condensers to make possible very close connections within the vacuum chamber; and to provide a compact arrangement of loud-speaker, antenna, rectifier, and detecting or transmitting units. Other objects will appear from the following description:

Figure I is a plan view of the cabinet with top covers removed.

Figure II is a vertical section of the cabinet giving an interior view.

The radio cabinet is enclosed by walls 1, base 2, and cover 3. It contains a compartment 4 holding a loudspeaker 5, and a compartment 6 holding a parabolic cylindrical reflector 7, and the telescoping rod antenna 26. The sealed vacuum chamber 8 contains such elements as a holder 9 with standards 10, supporting adjustable condenser plates 11 with leads 12, holders 13 with notched standards 14, supporting cathodes 15, multiple grids 16, and plates 17; and the radio frequency transformer 18. Screws 19, passing through cover 20 and gasket 21 into threaded holes 22, serve to make the chamber air-tight. It is then evacuated through tubes 23 cemented or threaded into the cover 20, and the tubes pinched off.

Short wires 24 built or cemented into the walls 25 of the vacuum chamber 8 serve for connecting the elements inside the chamber with those on the outside. Instead of these wires, holes 27 could be left and the leads from the elements inside drawn through them and then surrounded with cement to completely close the openings.

Additional compartments 28 and 29 adjoining the vacuum chamber 8 may also be exhausted of air for additional sets of detector or transmitter elements, or may be left unsealed and used for rectifying tubes, power supply 31, and the like.

In the past each set of plate, grid, and cathode

elements have been placed in a separate tube, and the considerable length of the leads between tubes has lengthened the wavelength being transmitted. By placing several sets of such elements in a common vacuum chamber my improvement makes possible shorter connections between elements and a more flexible arrangement for securing a minimum of inductance and consequent ultra short waves. Condensers, radio frequency transformers, resonance coils, and any other parts desired may, by my device, be enclosed in the same chamber. For multiple stage amplification any number of element sets may be enclosed in one chamber and connected in any manner desired.

By providing a removable cover 20 for the vacuum chamber 8, and multiple or removable threaded exhaust tubes 23, it is possible to open the chamber at any time for the replacement, 20 substitution, or rearrangement of elements, and then to replace the cover and reexhaust the chamber. The vacuum chamber 8, of glass, plastic, or other dielectric material, may be entirely removed from the cabinet if desired and replaced by another.

Cooperating groups of elements, such as cathodes, grids, and plates, are placed upon plastic, glass, or porcelain mounts 13 having grooved standards 14 to hold them in proper relation. 30 The design of these mounts makes possible sufficient spacing and insulation for the very high voltages employed in transmission.

Leads 30 at both ends of plate 17 are provided to facilitate multiple connections between elements and to give a choice for possible shorter connections. Grid and cathode elements are similarly provided with double leads. For a more perfect seal two superimposed, spaced covers may be used for the vacuum chamber 8, if desired.

40 I claim:

A unit for a radio tube comprising a dielectric base, standards rising from said base and integral therewith, notches in the top of said standard, and cathode, grid, and plate elements suspended 45 between said standards and held in place by said notches.

ABRAHAM BINNEWEG, JR.
